ELECTROLYTIC CELL

William C. Gardiner, Niagara Falls, N. Y., assignor to The Mathieson Alkali Works, Inc., New York, N. Y., a corporation of Virginia

Application October 16, 1941, Serial No. 415,276

5 Claims. (CL 204—247)

1

My invention relates to improvements in electrolytic cells for the production of light metals from fused salt baths heavier than the metal, particularly for the production of magnesium from fused salt baths containing magnesium chloride. The improvements of my invention afford important economies with respect to cell construction, maintenance and operation, and, as applied to fused chloride baths, facilitate the separation and recovery of chlorine liberated by the electrolysis in high concentration and of high purity.

The improved electrolytic cell of my invention is characterized essentially by an apertured, horizontal partition disposed below the normal bath level in the cell chamber and by the relationship of this partition to the other parts of the cell. The anodes, for the electrolysis, are suspended through the apertures in this partition, and the cathode elements, disposed around the anodes, and non-conducting sleeves, extending downwardly from the periphery of the apertures through which the anodes are suspended, are suspended from the partition. The other parts of the cell of particular importance with respect to my invention comprise the elements establishing the circulatory path of the fused electrolyte and those establishing the compartment for charging the salt to be electrolyzed to the bath, the compartment for collecting the liberated metal and the compartment for collecting gas liberated by the electrolysis. My invention also includes a particular arrangement of the cathode elements and a particular proportioning of the horizontal area of the annular spaces between the sleeves suspended from the partition and the anodes suspended through the apertures in the partition and these sleeves.

An electrolytic cell embodying my invention is illustrated in the accompanying drawings. In these drawings, Figure 1 is a vertical section, with certain details omitted, through the cell showing the charging compartment (at the right), the electrolysis compartment (at the lower left) and the gas collection compartment (upper left), on line 1—1 of Figure 2; Figure 2 is a plan of the cell; Figure 3 is a vertical section showing the metal collection compartment (at the upper right), the electrolysis compartment (at the lower left) and the gas collection compartment (at the upper left) on line 3—3 of Figure 2; and Figure 4 is a vertical section through the charging compartment on line 4—4 of Figure 2.

The horizontal partition characteristic of my invention is designated 5 in the drawings and is 55

2

constructed in the cell illustrated of steel plate protected and insulated on its upper surface by appropriate refractories 6. The fact that this partition can be constructed in this manner contributes materially to the advantages of my invention. This horizontal partition 5 is disposed below the normal bath level, indicated at A in Figures 1 and 3, within a cell chamber 7 and two sides of this partition are separately spaced from 10 the chamber walls to provide a free surface in the charging compartment through which the electrolyzed salt can be introduced into the fused electrolyte and through which any liberated water, for example, can escape from the cell and 15 to provide a separate free surface in the metal collection compartment from which the metal produced by the cell can be removed, all without exposure of the fused electrolyte in the electrolysis compartment and without requiring access to the gas collection compartment or passage of 20 salt being charged to the cell through this compartment. The charging compartment and the metal collection compartment may be arranged along adjacent sides of the horizontal partition 5, as in the cell illustrated, or they may be arranged 25 along opposite sides of this partition. Also the charging compartment may be arranged along one side of this partition and metal collection compartments along both of the adjacent sides. 30 In the cell illustrated, the charging compartment 8 and the metal collection compartment 9 are separated by the partition, or inverted dam, 10 which, as indicated in Figure 4, extends entirely 35 across the upper part of this side of the cell chamber.

The anodes 11, carbon rods, are suspended through the indicated apertures in the horizontal partition 5. These anodes, severally, are supported by the roof of a bell 12 forming a gas collection chamber above the partition 5. Each anode is carried by a water-cooled yoke 13, which may also serve as the anode terminal, by nuts on threaded pillars 14 secured to the roof of the bell 12, facilitating vertical adjustment of the anodes. Each anode passes through a gas-tight seal on the roof of the bell made up of a pair of refractory bushings 15 and 16 and a packing of asbestos rope 17 and powdered magnesia 18 (see Figure 1). The roof of the bell is provided with a water-cooled jacket space 19 (see Figs. 1 and 3) to which water may be supplied and from which it may be discharged via inlet aperture 19a and outlet aperture 19b, respectively (see Fig. 2). A non-conducting sleeve 20, of appropriate refractory material, passing through the apertures in

the partition 5 and extending downwardly from the periphery of these apertures and supported by the partition 5, is disposed around each of the anodes. These sleeves 20 are with special advantage so proportioned with respect to the anodes 11 and the cell capacity that the aggregate horizontal areas of the annular spaces between these sleeves and the anode approximate 0.014 square inch per ampere of cell capacity for operation with fused chloride baths. With this proportioning, effective circulation of the fused electrolyte within the cell is maintained by the chlorine liberated at the surface of the anode in the electrolysis compartment and rising through the annular spaces between the sleeves 20 and the anodes 11 into the gas collection compartment without excessive foaming or frothing in these annular spaces or in the compartment above the horizontal partition 5. The cell illustrated can be enlarged by extending the cell along an axis normal to the section illustrated in Figure 1 and by a corresponding extension of the horizontal partition and the provision of additional pairs of anodes and groups of cathode elements similarly arranged. The anodes may conveniently number from two to ten, for example.

In the illustrated cell, the cathode elements consist essentially of steel rods 21, suspended from the partition 5 and extending well below the lower rims of the sleeves 20. As illustrated, the rods 21 are reinforced at their upper and lower ends, respectively, by hoops 22 and 23. The rods 21 are disposed as elements of inverted frustoconical surfaces, that is with the larger base of the frustoconical section at the top, at all points more remote from the adjacent anode than the projection at the same level of the inner surface of the corresponding sleeve 20. The cathode elements may be otherwise disposed, for example as a cage or net, but are with advantage disposed as elements of inverted frustoconical surfaces at all points more remote from the adjacent anode than the projection at the same level of the inner surface of the corresponding sleeve irrespective of their arrangement or configuration in other respects. The arrangement of the anode elements also should permit free circulation of the fused electrolyte into and through the space between the anode and the cathode elements. The cathode elements are with advantage electrically connected to a steel plate forming the partition 5, by welding for example, and thus connected to the cell chamber, of cast steel or steel plate for example, to which the cathode terminal is then affixed.

An inverted dam 24, that is a dam establishing flow beneath itself, extends downwardly from that side of the partition 5 spaced from the wall of the cell chamber 1 to form the charging compartment 8, preferably to a level somewhat below the lower ends of the anodes and cathodes in the electrolysis compartment. This dam may be of steel plate, and may be connected electrically to a steel plate forming the partition 5. The inverted dam 10 extends downwardly from above the bath level to below the bath level above this same side of the partition 5. In the cell illustrated, flow beneath this dam is through the openings 25 shown in Figures 1 and 4. These two inverted dams, 10 and 24, establish a circulatory path within the cell, upwardly from the electrolysis compartment between the anodes 11 and the sleeves 20 to the space above the partition 5 and below the bath level, then beneath the inverted dam 10 to the charging compartment, and then downwardly

through the charging compartment to the lower part of the cell chamber and beneath the dam 24 back to the electrolysis chamber. The salt to be electrolyzed is supplied to the fused electrolyte circulating within the cell chamber to maintain the concentration of this component as it is consumed by the electrolysis by introduction into the charging compartment 8, for example, through removable covers 26 or through a connection 27. 5 In the feeding compartment, the salt thus supplied is fused and incorporated into the circulating fused electrolyte moving from the charging compartment to the electrolysis compartment beneath the inverted dam 24. In the production of 10 magnesium, magnesium chloride may thus be supplied to a fused electrolyte comprising, in addition to magnesium chloride, one or more of a variety of salts such as sodium chloride, sodium fluoride, potassium chloride, calcium chloride and 15 calcium fluoride. The magnesium chloride may thus be supplied as the anhydrous salt or it may be supplied in hydrated condition, for example as the dihydrate, in which event dehydration is also effected in the charging compartment, liberated water being exhausted through connections 28 to 20 appropriate evacuating equipment. The arrangement of the dams 10 and 24 just described, and illustrated in the drawings, also makes the charging compartment an advantageous means of access for dredging the cell to eliminate solids settling from the fused electrolyte within the cell chamber, solids such as magnesium oxide in the electrolysis of magnesium chloride. To facilitate such dredging of the cell, the cell chamber 1 is 25 with advantage arranged with a bottom sloping toward the side beneath the charging compartment, as illustrated in Figure 1, to form a collection trough 29 to which direct access can be had through the charging compartment. This 30 configuration of the bottom of the cell chamber, particularly with respect to the inverted dam 24, also promotes settling of any suspended impurities in the fused electrolyte at this point. If 35 hydrous magnesium chloride is introduced into the charging compartment, for example, any magnesium oxide produced by hydrolysis during dehydration of such magnesium chloride in the charging compartment tends to settle in the trough 29 as the fused electrolyte circulates beneath the dam 24 before entering the electrolysis chamber. With this arrangement, any external firing of the cell chamber to assist in maintaining temperatures necessary for fusion of the electrolyte during operation is with advantage limited to that part of the cell chamber to the left 40 of the point approximately located at "C" in Figure 1.

An auxiliary dam 30 (see Figure 1) extending upwardly from the partition 5 below the bath level and spaced from and paralleling the side of this partition beneath the dam 10 and above the dam 24 is with advantage provided to assist in maintaining the uniformity of flow of the fused electrolyte, particularly through the charging 45 compartment, and also assists in effecting complete separation of gas liberated by the electrolysis in the space above the partition 5. Gas separated in the space above partition 5 may be withdrawn from the gas collection compartment 31 through vent 41.

The metal liberated on the cathode elements in the electrolysis compartment rises through the fused electrolyte to the lower side of the partition 5 beneath which it is trapped by that part of the sleeves 20 extending downwardly from the periph-

ery of the apertures through the partition 5. The disposition of the cathode elements previously described, particularly in the electrolysis of fused chlorides with the proportioning previously described, effectively secures substantially complete recovery of the liberated, fused metal as a layer beneath the partition 5 of depth less than the extension of the sleeves 20 below the partition 5. The lower rims of the sleeves 20 may be beveled, as indicated in Figures 1 and 3, to facilitate this collection of the liberated metal. The liberated, fused metal flows from beneath the partition 5 into the metal collection compartment along that side of the partition 5 beneath the partition 31 extending upwardly from the partition 5 (see Figure 3) where it floats on the fused electrolyte at a somewhat higher level, indicated at "B" in Figure 3, than the bath level because of the lower density of the liberated metal. The partition 31, in conjunction with the partition 5, the end of the partition 10 extending beyond the partition 5 and the walls of the cell chamber connecting these two partitions, establish the metal collection compartment 9. Removable covers 34, 35 and 36, are provided to facilitate removal of the liberated metal collected in the compartment 9. The sides of the removable covers 34, 35 and 36 adjacent the partition 31 are supported by the support 32 (see Fig. 3). The opposite edges of these covers may be supported by an inward extension 43 of the wall of the cell chamber 7, as shown in Fig. 3.

The gas collection compartment 31 above the horizontal partition 5 is formed by a gas collecting bell with its lower edge disposed below the bath level but spaced above that side of the partition over which the electrolyte flows to the charging compartment. In the cell illustrated, this bell 12 is made up of a water-cooled roof and walls fabricated of steel plate and lined with appropriate refractories 38. A gas tight gas collection chamber is thus assured. The walls of the bell extend downwardly to a level below the bath level and within the walls of the cell chamber and, with advantage, into a groove arranged to conform to the lower edge of the bell to permit insulation of the metal elements of the bell structure from the anode in order to prevent liberation of traces of metal by electrolysis above the partition 5. In the cell illustrated, this groove appears at 39 (see Figures 1 and 3). In practice, that part of this groove adjacent the metal of the bell structure is packed with a refractory cement and the inner part of the groove is left open. In the electrolysis of magnesium chloride, for example, magnesium oxide tends to accumulate in the remaining portion of the groove to form a frangible and non-conducting seal. The space between the walls of the bell and the surrounding walls of the cell chamber 7 and the partitions 10 and 31 is advantageously packed with a pulverulent reducing material such as pulverized coke as indicated at 40 (see Figures 1 and 3). The metal elements of the cell structure, above the level of the horizontal partition 5, should be appropriately protected with refractory material against the fused electrolyte and the atmosphere above it. Acid-resistant brick and porcelain tile, capable of withstanding the temperatures involved, are appropriate refractories.

Electrolytic cells embodying my invention can be operated for the production of magnesium from magnesium chloride fusions, for example, with current capacities of about 3000 to 3500 amperes per anode using carbon anodes approxi-

mately 8 inches in diameter. The cell of the drawings is illustrated approximately to scale, the anodes of this cell being approximately 8 inches in diameter.

5 I claim:

1. In an electrolytic cell for the production of light metals from fused salt baths heavier than the metal, the improvement which comprises a cell chamber, a horizontal partition disposed below the normal bath level therein and separately spaced from the chamber walls on two sides said partition being shaped to provide apertures therein, anodes suspended through said apertures, non-conducting sleeves extending downwardly from the periphery of said apertures the upper end of said non-conducting sleeves being disposed below the normal bath level, a partition extending upwardly to the top of the cell chamber from one of said spaced sides of the horizontal partition, an inverted dam extending downwardly from the other of said spaced sides, an inverted dam extending downwardly from the top of the cell chamber to below the bath level above the spaced side last mentioned and forming a gas seal with the bath, cathode elements suspended from said horizontal partition and disposed around said anodes, and a trough in the bottom of the chamber to one side of the anodes and said inverted dam that extends downwardly from the horizontal partition with the sides of the chamber sloping downwardly to the trough.

2. In an electrolytic cell for the production of light metals from fused salt baths heavier than the metal, the improvement which comprises a cell chamber, a horizontal partition disposed below the normal bath level therein and separately spaced from the chamber walls on two sides, said partition being shaped to provide apertures therein, anodes suspended through said apertures, non-conducting sleeves extending downwardly from the periphery of said apertures the upper ends of said non-conducting sleeves being disposed below the normal bath level, a partition extending upwardly to the top of said cell chamber from one of said spaced sides of said horizontal partition, an inverted dam extending downwardly from the other of said spaced sides, a second inverted dam extending downwardly from the top of the cell chamber to below the bath level above the spaced side last mentioned and forming a gas seal with the bath, a dam extending upwardly from said horizontal partition and spaced from and paralleling the spaced side last mentioned, said upwardly extending dam being positioned between the inverted dam last mentioned and the anodes and terminating at its upper end below the bath level, and cathode elements suspended from said horizontal partition and disposed around said anodes.

3. In an electrolytic cell for the production of light metals from fused salt baths heavier than the metal, the improvement which comprises a cell chamber, a horizontal partition disposed below the normal bath level therein and separately spaced from the chamber walls on two sides, said partition being shaped to provide apertures therein, anodes suspended through said apertures, non-conducting sleeves extending downwardly from the periphery of said apertures the upper ends of said non-conducting sleeves being disposed below the normal bath level, cathode elements suspended from said horizontal partition and disposed around said anodes and extending below said sleeves, said cathode elements consisting essentially of spaced down-

wardly extending rods disposed as elements of inverted frustoconical surfaces at all points more remote from the adjacent anode than the projection at the same level of the inner surfaces of the corresponding sleeve, said rods being held in such a position by rings disposed around the anodes, a partition extending upwardly to the top of said cell chamber from one of said spaced sides of said horizontal partition, an inverted dam extending entirely across the cell chamber and 10 downwardly from the other of said spaced sides of said horizontal partition, a second inverted dam extending entirely across the cell chamber and downwardly from the top of the cell chamber to the upper edge of the inverted dam first mentioned and forming a gas seal with the bath, said second-mentioned inverted dam being shaped to provide a passageway positioned above said horizontal partition and below the normal bath level, and a dam extending upwardly from said 15 horizontal partition and spaced from and paralleling the spaced side last mentioned, said upwardly extending dam being positioned between the inverted dam last mentioned and the anodes and terminating at its upper end below the bath level.

4. In an electrolytic cell for the production of light metals from fused salt baths heavier than the metal, the improvement which comprises a cell chamber, a horizontal partition disposed below the normal bath level therein and separately spaced from the chamber walls on two sides, said partition being shaped to provide apertures therein, anodes suspended through said apertures, non-conducting sleeves extending downwardly from the periphery of said apertures the upper ends of said non-conducting sleeves being disposed below the normal bath level, cathode elements suspended from said horizontal partition and disposed around said anodes and extending below said sleeves, the aggregate horizontal areas of the annular spaces between said sleeves and said anodes approximating 0.014 square inch per ampere of cell capacity, a partition extending upwardly to the top of said cell chamber from one of said spaced sides of said horizontal partition, an inverted dam extending entirely across the cell chamber and downwardly from the other of said spaced sides of said horizontal partition, a second inverted dam extending entirely across the cell chamber and down-

wardly from the top of the cell chamber to the upper edge of the inverted dam first mentioned and forming a gas seal with the bath, said second-mentioned inverted dam being shaped to provide a passageway positioned above said horizontal partition and below the normal bath level, and a dam extending upwardly from said horizontal partition and spaced from and paralleling the inverted dam last mentioned, said upwardly extending dam being positioned between the inverted dam last mentioned and the anodes and terminating at its upper end below the bath level.

5. In an electrolytic cell for the production of light metals from fused salt baths heavier than the metal, the improvement which comprises a cell chamber, a horizontal partition disposed below the normal bath level therein and separately spaced from the chamber walls on two sides, said partition being shaped to provide apertures therein, anodes suspended through said apertures, non-conducting sleeves extending downwardly from the periphery of said apertures the upper ends of said non-conducting sleeves being disposed below the normal bath level, cathode elements suspended from said horizontal partition and disposed around said anodes and extending below said sleeves, a partition extending upwardly to the top of said cell chamber from one of said spaced sides of said horizontal partition, an inverted dam extending entirely across the cell chamber and downwardly from the other of said spaced sides of said horizontal partition, a second inverted dam extending entirely across the cell chamber and downwardly from the top of the cell chamber to the upper edge of the inverted dam first mentioned and forming a gas seal with the bath, said second-mentioned inverted dam being shaped to provide a passageway positioned above said horizontal partition and below the normal bath level, a dam extending upwardly from said horizontal partition and spaced from and paralleling the inverted dam last mentioned, said upwardly extending dam being positioned between the inverted dam last mentioned and the anodes and terminating at its upper end below the bath level, and a gas collecting bell disposed above said horizontal partition with its lower edge extending below the normal bath level.

WILLIAM C. GARDINER.
